[57] CLAIM

The ornamental design for a vehicle body straightening tilttable rack, as shown and described.

DESCRIPTION

FIG. 1 is a top plan view of a vehicle body straightening tilttable rack, showing my new design;

FIG. 2 is a side elevational view taken from the bottom of FIG. 1, the broken line showing of the removable tire receiving tracks for illustrative purposes only;

FIG. 3 is an end elevational view taken from the right of FIG. 2, the end opposite being a mirror image thereof;

FIG. 4 is a bottom plan view thereof.

FIG. 5 is a side elevational view taken from the side opposite that shown in FIG. 2.

FIG. 6 is a perspective view thereof.
